[57] CLAIM

The ornamental design for a quick release strap, as shown and described.

DESCRIPTION

FIG. 1 is a perspective view of the quick release strap showing my new design;

FIG. 2 is an unbuckled exploded perspective view thereof;

FIG. 3 is a top plan view thereof, the bottom view being identical;

FIG. 4 is a left side elevational view thereof, the right side being a mirror image;

FIG. 5 is a front elevational view thereof;

FIG. 6 is a rear elevational view thereof;

FIG. 7 is a top plan view of the female component, the bottom view being identical;

FIG. 8 is a left side view of the female component, the right side being a mirror image thereof;

FIG. 9 is a front elevational view of the female component;

FIG. 10 is a rear elevational view of the female component;

FIG. 11 is a top plan view of the male component, the bottom view being identical;

FIG. 12 is a right side view of the male component, the left side being a mirror image thereof;

FIG. 13 is a front elevational view of the male component; and,

FIG. 14 is a rear elevational view of the male component.
